UNITED STATES PATENT OFFICE.

ROY W. LONGLEY AND WILLIAM H. GRAY, OF MONROE, MICHIGAN.

GLUE MACHINE.

Application filed July 3, 1924. Serial No. 723,963.

To all whom it may concern:

Be it known that we, ROY W. LONGLEY and WILLIAM H. GRAY, citizens of the United States, and residents of Monroe, in the county of Monroe and State of Michigan, have invented a new and useful Glue Machine, which invention is fully described in the following specification.

Our invention has for its object to provide a glue machine having glue-feeding rotary members wherein the location and the length of the glue spread may be regulated. The invention particularly provides an automatic means for causing the glue spreading operations to begin at a certain point on an article that is to receive the glue and to continue the glue-spreading operation up to another point on the said article. Thus by our invention is provided a means whereby articles may be fed relative to the glue spreading part of the machine, and at predetermined points or spaces, become covered with a film of glue of the proper thickness, preparatory to becoming attached to some other part of the article or to some other article by drying of the glue when in contact with such other part or other article.

The invention may be contained in gluing machines of different types and in automatic controlling devices of different forms for controlling the articles relative to the glue-spreading parts of the glue machines. To illustrate a practical application of the invention we have selected a glue machine containing the invention and shall describe it hereinafter. The structure selected is illustrated in the accompanying drawings.

Figure 1 of the drawings illustrates an end view of the glue machine. Figure 2 illustrates a side view of the automatic controlling device for controlling the length of the spread of the glue that is fed to the article by the machine. Figure 3 is a side view of a part of the machine shown in Fig. 1. Figure 4 is a top view of one of the guides for the article that receives the glue. Figure 5 is an enlarged top view of the guide. Figure 6 is an edge view of the guide showing it in its position relative to the glue-feeding disc.

In the structure selected as an example of embodiments of our invention, the glue machine feeds the glue to the article from above, means being provided for directing the articles beneath the glue pots. In the form of glue machine shown in the draw-

ings, the glue is fed to the article by means of discs 10 that are connected to a shaft 11 that is driven by a suitable sprocket gear wheel 12 which is driven by a sprocket chain 13 that may be connected to a suitable source of power for causing rotation of the discs 10. The discs 10 are located in the glue pots 14 having the covers 15. The discs 10 protrude from the bottom of the pots 14, proper wiping and glue-retaining devices being provided within the pots to produce the proper regulated supply of glue to cause the formation of a film of glue on the articles of the desired thickness.

The articles are conveyed by suitable belts beneath the discs so as to receive the glue therefrom. The structure shown in the drawing is designed for spreading glue over sheet material, such as cardboard, and between predetermined points on the cardboard with respect to the ends of the cardboard. The cardboard 16 is directed beneath the glue pots and in proximity to the glue discs by means of the belts 17 and suitable feed rollers. The cardboard may be supported between the belts by any suitable means such as the strips 18 that are supported on the bed of the glue machine or any other suitable part of the frame of the glue machine. An automatic glue-spreading regulator 20 is supported so as to be engaged by the article 16 as it is being conveyed by the belt 17.

The automatic device is supported on a board 21 that is connected to uprights 22 forming a part of the glue machine, by means of threaded rods 23, and is secured in position by means of the nuts 24. The rods 23 extend through slots 19 whereby the regulator 20 may be longitudinally adjusted relative to the glue machine. A pair of levers 25 and 26 extend to a point below the upper surfaces of the belts 17 and the upper edges of the strips 18 and so as to be located in the path of the end edges of the cardboard 16. The lever 25 is pivotally connected to an adjustable plate 27 that may be adjustably secured to the board 21 by means of the bolts 28 that are located in the slot 29 formed in the plate 27. The lever 25 is also connected to a bar 31 by means of a pin 32 that is located in the slot 33 and secured to the bar 31. Thus the pin 32 may be adjusted with reference to the lever 25. Longitudinal movements of the bar 31 are produced by the rotative movements of the

lever 25, this change of direction of motion between the parts being permitted by the slot 34 through which the pin 32 extends. The bar 31 is guided in its longitudinal movements by means of the bracket 36 and the pin 37 that extends through the slot 33. Slight angular movements of the bar 31 may be produced away from the bracket 36 about the pin 37, the slot 34 being such as to permit the pin 32 to move along the arm of the lever 25. Thus the cardboard 16 holds the lever 25 in the position that it is turned by the forward edge of the cardboard and maintains the bar 31 in the position in which it is moved by the lever 25, while the board passes under the lever 25.

The bar 31 is provided with a notch 40 that is drawn from beneath the pin 41 located on a link 42. The link 42 is connected to the lever 26. The lever 26 is pivoted to the board 21 and when it is operated by the forward edge of the cardboard 16, while the lever 25 is being held in its position by the cardboard, the pin 41 engages the forward end of the bar 31 to draw it down about the pin 37. The link 42 is maintained in position by means of the pin 43 which is secured to the board 21 and the spring 44 that is connected to the link 42 and the board 21 to draw the upper end of the link 42 towards the forward end of the board 21 and against the pin 43. The pin 43 may be located in a notch formed in the upper end of the link 42 whereby the movement of the link 42 is limited by the length of the notch.

The downward movement of the forward end of the bar 31 is communicated to a shaft 45 supported in the standards 22 and 46. The bar 31 is connected to the shaft 45 by means of the rod or link 47 and the arm 48 to produce angular or rotative movements in the shaft 45. When, therefore, the rod 47 is pulled downward and the shaft 45 is given a short angular movement, it causes the outer ends of the arms 49 connected to the shaft 45 to be raised. This movement is communicated to the levers 50 by means of the rods 51.

The levers 50 are pivotally connected by means of brackets 52 secured to the bottoms of the glue pots 14. The levers 50 are pivotally supported by means of the shaft 53 that extend through the brackets 52. The shafts 53 extend across the bottoms of the glue pots, each lever 50 being located at one end of a shaft 53. The other end of the shaft 53 is connected to a guide 54 that guides the cardboard 16 relative to the discs 10, and rotative movement of the shafts 53 produced by the levers 50 raises the cardboard 16 so as to bring an edge portion of the cardboard into contact with the discs 10 to receive the glue from the discs.

The guide 54 is preferably formed of

sheet metal which is bent to form a channel through which each edge portion of the cardboard passes as it is being conveyed by the belt 17. The leading end of each guide may be provided with a flaring tongue 55 for receiving the end edge of the cardboard and directing it into the channel. The guide is provided with a recess 56 located in the upper side of the guide and which extends from the following end of the guide to a point in advance of the shaft 53 and so that when the guide 54 is tilted by the operation of the lever 50, the metal of which the guide is formed will not touch the discs 10. This will avoid the collection of glue on the guide but it will permit the disc to spread the glue on the cardboard as it passes through the guide, when the guide is tilted. Thus when the bar 31 is held in position so that the notch 40 is drawn from beneath the pin 41 and the forward end of the bar is pulled down by the operation of the lever 26, the guides 54 will be turned so as to lift the edges of the cardboard and cause the film of glue to be spread along edge portions of the cardboard. The controlling device 20 may thus be so located and the lever 25 may be so adjusted as to cause the gluing operation to start at predetermined desired points along the edges of the cardboard and until the guides 54 are permitted to dip down to lower the edges of the cardboard away from the discs 10.

The distribution or spread of the glue on the cardboard 16 is discontinued by the guides 54 being tilted downward so as to move side edge portions of the cardboard away from the discs 10. This movement is caused by the following edge of the cardboard 16 passing from beneath the lever 25. The bar 31 is connected to a spring 58 and the spring 58 is connected to a pin 59 that is secured to the board 21. The elasticity of the spring 58 draws the bar 31 along the pin 37 and the bracket 36 until the notch 40 is brought into alignment with the pin 41 located on the link 42, and notwithstanding the fact that the lever 26 is still held in a raised position, the bar 31 is permitted to swing upwards by the elasticity of the spring 58 until it strikes the pin 60. This raises the rod 47 which causes a return movement of the arm 48 and the shaft 45. This also causes a return movement of the arms 49 and the rods 51. This in turn operates the levers 50 to cause the guides 56 to dip downward. The levers 50 are also connected to springs 61 which coact with the spring 58 to cause the return of the guides 54 to their normal positions. As the cardboard 16 is carried along its following edge passes beneath the lever 26, which permits the lever 26 to return to its normal position. The link 42 is connected to a spring 62 which in turn is connected to the

board 21. The spring 62 draws the link 42 upward until it is stopped by the pin 43 and also moves the lever 26 to its normal position. Thus the mechanism is set ready to receive the succeeding cardboard. The cardboards may be fed through the machine as rapidly as may be desired, each successive cardboard receiving the glue during the desired periods of its travel through the guides. The glue thus may be deposited between points more or less spaced from the ends of the cardboard, as may be desired. Since the first contact of the cardboard with the discs 10 will deposit glue over a short length, the cessation of the spread of the glue must occur at a very short period in advance of the time when the points at the following ends of the glue films pass from beneath the discs. This difference in point of time is controlled by the adjustments of the levers 25 and 26 relative to each other. The distances of the ends of the glue films from the leading and following edges of the cardboard may be controlled or adjusted by the adjustment of the board 21 relative to the supporting rods 23. Thus the glue film may be deposited so as to leave end portions or corner portions of the cardboard free from the glue. The cardboard may then be folded for any purpose desired, such as to form an attractive and strengthened edge, or may be folded into the form of a box, or other articles or objects may be secured to the cardboard that has received the glue, as may be desired and according to the purpose for which the article is to be used.

We claim:—

1. In a glue machine, in combination with a glue spreading means, means for conveying the article beneath the glue spreading means, a guide for controlling the spreading of the glue, a lever controlled by the movement of the article for moving the guide into glue spreading relation and a lever controlled by the article for removing the article from the glue spreading relation.

2. In a glue machine, in combination with a glue spreading means, means for conveying the article beneath the glue spreading means, a tilting guide for moving the article into and out of glue-spreading relation to the glue spreading means, a means operated by the article for moving the guide in one

direction and a means operated by the article 55 for moving the guide in the opposite direction.

3. In a glue machine, in combination with a glue spreading means, means for conveying the article beneath the glue spreading 60 means, a tilting guide for moving the article into and out of glue spreading relation to the glue spreading means, a means operated by the article for moving the guide in one direction and a means operated by the article 65 for moving the guide in the opposite direction, a means for operating the guide to move the article away from the glue spreading means being operated in advance of the time that the following end 70 of the glue film placed on the article passes beneath the glue spreading means.

4. In a glue machine, in combination with a glue spreading means, means for conveying the article beneath the glue spreading 75 means, means for operating the glue spreading means to cause the glue to spread on the article, and means for operating the glue spreading controlling means for discontinuing the glue spreading on the article, the 80 last named means operating in advance of the period of time as measured by the movement of the article beneath the glue spreading means from the time that the article is brought into glue spreading relation. 85

5. In a glue machine, in combination with a glue spreading means, means for conveying the article beneath the glue spreading means, means for operating the glue spreading means to cause the glue to spread on the 90 article, and means for operating the glue spreading controlling means for discontinuing the glue spreading on the article, the 95 last named means operating in advance of the period of time as measured by the movement of the article beneath the glue spreading means from the time that the article is brought into glue spreading relation, and means for adjusting the glue spreading controlling means with reference to the article 100 and means for adjusting the lead of the operation of the means for causing cessation of the glue spreading on the article relative to the period of movement of the article.

In testimony whereof we have hereunto 105 signed our names to this specification.

ROY W. LONGLEY.
WILLIAM H. GRAY.
